UNITED STATES PATENT OFFICE.

HARRY L. COOPER, OF ALBANY, OREGON.

FIRE-ESCAPE.

960,510.

Specification of Letters Patent. Patented June 7, 1910.

Application filed February 28, 1910. Serial No. 546,439.

To all whom it may concern:

Be it known that I, HARRY L. COOPER, a citizen of the United States, residing at Albany, in the county of Linn and State of Oregon, have invented certain new and useful Improvements in Fire-Escapes; and I do declare the following to be a full, clear, and exact description of the invention, such as will enable others skilled in the art to 10 which it appertains to make and use the same.

This invention relates to improvements in fire escapes.

One object of the invention is to provide 15 a simple and improved form of portable fire escape by means of which a person may safely lower others and then himself from a burning building at any desired rate of speed.

Another object is to provide a device of 20 this character which will be strong and durable in construction, light in weight, efficient and reliable in operation, and which may be readily packed in a trunk or traveling bag.

With the foregoing and other objects in 25 view, the invention consists of certain novel features of construction, combination and arrangement of parts as will be more fully 30 described and particularly pointed out in the appended claims.

In the accompanying drawings, Figure 1 is a front view of a fire escape constructed 35 in accordance with my invention; Fig. 2 is a side view of the same; Fig. 3 is a central vertical section; Fig. 4 is a similar view taken at right angles to Fig. 3; Fig. 5 is a vertical section through the end of the reel shaft showing the handle having the braking mechanism swung down to an open position.

In the embodiment of the invention, I provide a combined handle and reel supporting frame 1 comprising side bars 2 connected at their upper ends by a handle bar 3. To the lower ends of the bars 2 of the frame 1 is hingedly connected a combined handle and brake carrying frame 4 comprising side bars 5, which are connected together at their upper ends by a handle bar 6, as shown. The ends of the bars 2 and 5 of the frames 1 and 4 are preferably hinged together by a rule joint connection as shown.

Journalized in suitable bearing plates 7 55 secured to the outer side of the bars 2 of the frame 1 adjacent to their lower ends is a

reel supporting shaft 8, on which between the bars 2 is fixedly mounted a strap winding reel 9, comprising a centrally disposed sleeve 10, which is secured to the shaft 8 60 by a set screw or other suitable fastening means and which is provided on its opposite ends with circular radially projecting flanges 11 to which are bolted or otherwise secured circular friction disks 12 forming 65 part of the braking mechanism. The lower ends of the bars 2 and 5 of the frames 1 and 4 are enlarged as shown and have formed in their inner edges substantially semi-circular notches which, when the frames are brought 70 together, engage the opposite sides of the shaft 8 near its outer ends thus exerting a braking action on the shaft, when the handles are drawn together.

To the sleeve 10 is secured the inner end 75 of a lowering strap 13 which may be of any suitable construction but which is here shown and is preferably formed of a light strong fiber. To the outer end of the strap 13 is secured a suitable hook or other fastening device 14 by means of which this end of the strap may be fastened to a window sill, an article of furniture, or other object sufficiently large and heavy to sustain 85 the weight of the person descending on the escape. On one end of the shaft 8 is arranged a crank handle 15 by means of which the reel may be operated to wind up the strap when desired. On the handle bar 3 of the frame 1 midway between the bars 2 90 and in line with the center of the reel is a strap guide 16, comprising brackets secured to one side of the bar 3 and having revolvably mounted between the same an anti-friction roller 17. When in use the strap 13 passes 95 from the reel up through the guide 16, whereby the frame 1 is guided in its descending movement.

To the side bars 5 of the frame 4, adjacent to their lower ends, is secured a braking 100 mechanism comprising a yoke or bail shaped frame 18, the ends of which are bolted or otherwise secured to the bars 5 of the frame 4 as shown. To the bail shaped frame 18 opposite each of the brake disks 12 is secured a segmental brake shoe or plate 19. When the frame 4 is swung upwardly, the brake shoes 19 are brought into engagement 105 with the edges of the brake disks 12 and by gripping the handle bars 3 and 6 of the frames 1 and 4, the brake shoes may be forced against the disks with any desired 110

pressure to retard the rotary movement of the reel, and thus regulate the unwinding of the strap and the consequent descent of the fire escape.

- 5 In the lower ends of the bearing plates 7 are formed eyes or apertures with which are adapted to be detachably engaged snap hooks or other suitable fastening devices 21 secured to the opposite ends of a supporting strap 22 which forms a loop or sling adapted to support the person descending on the fire escape.

By means of a fire escape constructed as herein shown and described, the outer or hook end of the strap 13 may be secured to a child or other person and the latter lowered from a burning building at any desired speed, after which the strap may be again wound up on the reel by the crank handle 15 and the hook end secured to the window sill or other object after which the operator may lower himself to the ground.

From the foregoing description taken in connection with the accompanying drawings, the construction and operation of the invention will be readily understood without requiring a more extended explanation.

Various changes in the form, proportion and the minor details of construction may be resorted to without departing from the principle or sacrificing any of the advantages of this invention as defined in the appended claims.

Having thus described my invention, what I claim is:—

1. In a fire escape, a reel supporting frame comprising a pair of side bars, a han-

dle-bar connected to the upper ends of said side bars, a reel revolvably mounted in the lower end of said frame, a crank handle connected with said reel, a lowering strap secured at its inner end to the reel and having on its outer end a fastening means, braking disks fixedly mounted on said reel, a brake carrying frame comprising side bars hingedly connected at their lower ends to the side bars of said reel frame, a handle bar connected to the outer ends of said side bars, a brake frame connected to said bars adjacent to their inner ends, brake shoes arranged in said frame to engage said disks, supporting plates secured to said reel frame, a body supporting strap, and means to detachably secure the ends of said strap to said supporting plates.

2. In a fire escape, a reel supporting frame, a handle connected therewith, a reel revolvably mounted in the frame, a lowering strap connected with the reel, braking disks fixedly mounted on the reel, a brake-carrying frame hingedly connected to the reel frame, a brake frame, brake shoes arranged in the brake frame to engage said disks, supporting plates secured to said reel frame, a body supporting strap, and means to detachably connect the ends of said strap to said supporting plates.

In testimony whereof I have hereunto set my hand in presence of two subscribing witnesses.

HARRY L. COOPER.
